MECHANISM FOR SELECTING AND OPERATING ANY DESIRED ONE OF A PLURALITY OF RODS OR THE LIKE

Charles Humphrey Humphreys, Carlton,
Bedford, EnglandApplication April 7, 1934, Serial No. 719,567
In Great Britain April 12, 1933

15 Claims. (Cl. 74—334)

The present invention relates generally to that type of apparatus in which a plurality of slideable members (for use, say, in the engagement and disengagement of the gears of a gear box upon a vehicle) are controlled by locking means adapted to be pre-selected for release, and in which any member whose lock has been so selected is biased for release by a spring so that said release may be completed on the return of the 5 any previously displaced member to neutral, such return being carried out and rendered effective on the locking means by the action of an element common to all the slideable members such as the control member of an engine clutch.

15 Now the object of the present invention is to provide an improved mechanism of the above general character for selecting for movement and operating any desired one of a plurality of movable members.

20 Although of general use in the pre-selection and operation of any members, the invention is particularly adapted for use in the engagement and disengagement of the gears of a gear box for automobiles, for example, since the driver has 25 only to pre-select the particular gear to be engaged and then to operate the control member, which may conveniently consist of the usual clutch-operating pedal, whereupon the desired gear will be engaged simultaneously with the return to the inoperative or neutral position of any 30 other gear which is engaged at the time of the pre-selection of the chosen gear.

According to my invention, the selector device, which may be a multiple cam disc, functions 35 to change a positive lock to a friction held lock the latter being subsequently released by a simple movement of the control common to the slideable members such as the engine clutch control.

40 In a preferred embodiment of the invention the construction of the selector device is such that when one of the locking devices is selected for release any other locking device which may then be in a released position is positively selected 45 for return to its operative or locking position.

45 Preferably also the slideable members will be arranged so as normally to tend to take up an operative position, the locking devices being held in place by reason of such tendency and the 50 selecting means each being adapted to exert a releasing force on one of said locking devices and means being provided for overcoming the tendency of the slideable members to take up operative positions, thus allowing the selecting means 55 to effect withdrawal of the locking devices.

In one constructional embodiment of the invention, said slideable members are associated with selecting devices comprising pivoted locking levers which normally act to hold the members against movement even though one of the 5 said members has been selected for movement, said selecting devices also being so constructed and arranged that after all the members have been moved initially to free the locking devices, any one of the selecting devices can act to bring 10 the selected locking device into an inoperative position in which the member is free to slide. When this construction is applied to the gear box of an automobile vehicle some or all of the slideable members may be arranged to be operative in pairs and, to this end, they may be interconnected in such a manner that when one of the members of a pair moves into the operative position, the other member will be returned to the inoperative or neutral position. The said 15 members may consist of slideable shafts, blocks or saddles or the like, which are arranged to be moved into the operative position under the action of springs and to be returned into the inoperative or neutral position by positively 20 acting means.

One or more of the members to be moved may be adapted to occupy two operative positions, one on one side of a neutral position and the other on the other side thereof.

30 The pivoted locking means are conveniently arranged to be operated by one or more turnable or slideable members, which act to bring the desired slideable member into a releasable position and simultaneously to bring the other slideable 35 members into a locked position or to allow them to remain in that position. The pivoted locking means of the locking and selecting device are loosely connected to their corresponding selecting devices and the latter on being moved for 40 selection are adapted to exert a force tending to withdraw their associated locking devices from their operative positions. For this purpose, the locking means and selecting devices each comprise a pivoted lever or levers, the locking and selecting levers being resiliently interconnected either directly or indirectly and the arrangement being such that the selecting lever or levers can be moved independently of the locking lever but then exerts a force thereon by reason of its 45 resilient connection therewith. This result may be effected in various ways. For example, each selecting device may comprise a pair of fingers or feelers held in contact with the opposite surfaces of a cam plate by means of a spring. The 50 55

selecting device may also comprise a pawl which, by co-operation with the corresponding slidable member, acts to retain the latter against movement until it is released under the action of said 5 positively acting means, whereupon said spring means acts to force the pawl out of engagement with the slidable member. Instead of employing a pair of fingers, however, a single resilient finger, guided by cam faces, may be used to obtain the 10 same result. The said cam plate may be operatively connected to a control lever arranged to work over a quadrant disposed within easy reach of the operator and the said positively acting means may consist of one or more slidable blocks 15 or the like which, by contact with the slidable members, or some of the latter, acts to release the pawl co-operating with the selected slidable member and also to return to the inoperative or neutral position any of the other slidable members which may have been moved previously 20 to the operative position.

Other constructional forms of the invention and the application of the invention to gear boxes of automobile vehicles are referred to in the description which follows.

Several constructional forms of the invention, applied to gear boxes of automobile vehicles, are shown by way of example, on the accompanying sheets of drawings, whereon:—

30 Fig. 1 is an elevation of one construction comprising slidable shafts;

Fig. 2 is a plan view corresponding to Fig. 1;

Fig. 5 is a fragmentary view, partly in section; showing the selecting device and locking pawl for some of the slidable shafts;

40 Fig. 6 is a view corresponding to Fig. 5, but showing the locking pawl disengaged from the shaft;

Fig. 7 is a fragmentary view of the selecting means and locking device used for the other shafts;

45 Fig. 8 is a sectional elevation of a modified form of the mechanism;

Fig. 9 is a section on the line C—D in Fig. 8, looking in the direction of the arrows D;

50 Fig. 10 is a section on the line E—F in Fig. 8, looking in the direction of the arrows C.

Fig. 11 is a sectional elevation on the line X—Y in Fig. 8, looking in the direction of the arrow G.

Fig. 12 is a view of the strips or plates to which the striker forks are connected;

55 Fig. 13 is a sectional plan of a further modification:

Fig. 14 is a sectional elevation corresponding to Fig. 13;

Fig. 15 is a fragmentary view, partly in section, showing three of the slidable blocks used in this modification;

Fig. 16 is a section on the line A—B in Fig. 13, looking in the direction of the arrows;

60 Fig. 17 is a section on the line C—D in Fig. 13, looking in the direction of the arrows;

Fig. 18 is a view illustrating a modified method of operating a striker fork by means of two members mounted on a slidable shaft.

Fig. 19 is a view of modified auxiliary locking 70 means for slidable shafts.

Fig. 20 is a view illustrating a further modified method of operating a striker fork by two members mounted on a slidable shaft.

Referring first to Figs. 1 and 2, to the lower 75 part of the clutch pedal 1 a rod 2 is pivotally

secured by means of a yoke-member 3, said rod being connected to a slidable shaft 4 by a coupling 5 so that the arcuate movement of the pedal will cause the shaft to be moved rectilinearly. The shaft is provided with a key 6 and slides in 5 a frame-like structure comprising two end plates 7 and 8, which are connected by bars 9. The plate 7 carries a sleeve 10 to which a collar 11, provided with an arm 12 whereby it may be rotated, is fixed. The sleeve 10 extends through the 10 plate 7 and is provided at its inner extremity with a cam disc 13 formed with a number of spaced cams 14, as shown in Figs. 1 and 4. The cams 14 co-operate with five pairs of feeler-arms 15 to form the gear selecting mechanism, the collar 15 11 being rotated until a particular cam engages with the desired pair of feeler-arms to effect the selection. Five feathered shafts 16, 17, 18, 19 and 20 are slidably arranged at the upper parts of the end plates 7 and 8, two similar shafts 21 and 20 22 also being slidably arranged at the lower parts of said plates and adapted to communicate their movements to the shafts 17 and 19 through levers 23 and 24. The lower ends of the levers 23 and 24, see Figs. 1 and 3 project through slots cut in 25 the shafts 21 and 22 respectively, whilst the upper ends of the levers pass through similar slots cut in the shafts 17 and 19. Sleeves 25 are arranged over the slotted parts of the shafts 17, 19, 21 and 22 and are provided with shorter 30 slots so as to allow a certain latitude of adjustment. Each of the levers 23 and 24 is pivotally supported by a fork-member 26 secured to the end plate 8 as shown in Fig. 1.

Blocks 27, 28 and 29 are fixed respectively to 35 the shafts 16, 18 and 20, the block 27 carrying a striker-fork 27A and being adapted to control the movement of the reverse gear of the gear-box to which the mechanism is fitted. The said block is also pulled in the direction shown by the arrow 40 in Fig. 2, by means of a tension spring 30, secured at its opposite end to a hook 31 fixed to the end-plate 8. In the position shown in Figs. 1 and 2, the reverse striker-fork 27A is not in the gear-engaging position but, as soon as it is released as 45 described hereinafter, it will move rearward together with the shaft under the action of the spring 30, and will carry out the gear engagement. The block 28 is provided with an arm 32 to which one end of a tension spring 33 is fixed, 50 the opposite end of the latter being attached to the sleeve 25 on the rod 17 by means of a pin 34. The block 29 is provided with an arm 35 to which one end of a spring 36, which is also attached to a pin 37 on the sleeve 25 on the shaft 19 is se- 55 cured.

Saddles 38 and 39 are slidably mounted on the shafts 17 and 19 and are formed with lateral extensions 40 and 41 which slidably embrace the adjacent shafts 18 and 20 and carry striker forks 60 42 and 43 adapted to actuate the first and second, and third and fourth gears, respectively. Forward movement (i. e. in a direction towards the clutch-pedal 1) of the fork 42 results in the engagement of the first gear and movement thereof 65 in the opposite direction results in the engagement of the second gear. Forward movement of the fork 43 causes engagement of the third gear and movement in the reverse direction, the engagement of the fourth or top gear.

The two levers 23 and 24 are provided for reversing the direction of movement of the shafts 21 and 22, in order that the forks 42 and 43 may be movable in both forward and backward direction. It is clear, therefore, that the shafts 17 and 75

19 are provided merely to convey the reversed movements of said shafts 21 and 22. Thus, it is necessary to select the shafts 21, 22, 16, 18 or 20 only, the selection of the shafts 17 and 19 being entirely dependent upon the shafts 21 and 22. The tendency of the springs 33 and 36, is to pull the block 28 and the sleeve 25 on the shaft 17 and the block 29 and the sleeve 25 on the shaft 19 towards each other, with the result that the shafts 21 and 22, as well as the shafts 16, 18 and 20, move backwards i. e. away from the clutch-pedal 1, when released. Thus, when the mechanism is in its neutral position, as shown in Figs. 1 and 2, the shafts which are to be selectable all tend to move 15 backwards but they are restrained from so doing, however, until selected by one of the selector cams 14.

As shown in Figs. 4, 5, 6 and 7 each of the shafts to be selected is provided with a pair of feeler arms 15 supported on a pin 45 provided in a bracket 44, a tension spring 46 being mounted between each pair of arms 15 so that the arms are drawn towards each other but are held apart by means of the cam disc 13. Arranged between each pair of arms 15 is a pin 47 which is supported by the two parts 48 of a bifurcated arm of a bell crank lever, whose other arm 49 is made in the form of a locking pawl. In Fig. 7, which illustrates also the arrangement adopted for the shaft 16, the locking pawl 49 is shown in engagement with the underside of the block 29 on the shaft 20, the extremity of the pawl contacting with an abutment 50. As stated above, the shafts 16 and 20 tend to move backwards, so that the pawl 49 will normally be held in position at the back of the abutment 50.

The arrangement for the selection of the shaft 21 and also of the shaft 22 is shown clearly in Figs. 5 and 6. In these two cases, the locking pawl 49 engages directly in a recess 51 cut in the shaft 21 or 22, as the case may be. The same arrangement is used in the case of the shaft 18, see Fig. 4. The shafts 21 and 22 are provided, respectively, with blocks 52 and 53, see Figs. 1 and 4, said blocks being cut away, see also Figs. 5 and 6, in order to allow the pawls 49 to engage in the recesses 51.

Referring to Fig. 6, when a cam 14 moves between a pair of the feeler arms 15, one of the arms 50 is moved laterally, whilst the other, shown in chain-dotted lines, remains unmoved. The spring 46 is thus stretched by the movement of the one arm and tends to draw the other arm over to the position shown in full lines but no such movement can take place because of the pin 47. The latter and also the pawl 49 still retain the positions indicated by the chain-dotted lines. The spring 46 tends to withdraw the pawl 49 from the shaft 21, but the spring-pressure upon the latter tending to draw it away from the plate 1 is sufficient to hold the pawl in engagement with the recess 51 by reason of the friction between the pawl and shaft. The latter is thus locked against movement until it is acted upon by a force sufficient to counteract the pressure of its spring tending to draw it backwards. In order to provide such a force, a heavy disc member 54 is securely mounted upon the shaft 4 and is adapted to co-operate with an abutment 55 on the block 52 to reduce the contact pressure between the pawl 49 and shaft 21. The spring 46 withdraws the pawl from the shaft whereupon the latter is free to slide backwards under the action of its own spring. It should be noted that the release of the pawl is carried out practically non-frictionally.

There is substantially no wear, which is important from the point of view of reliability.

The blocks 27, 28, 29 and 53 are provided respectively with abutments 56, 57, 58 and 59 corresponding to the abutments 55 on the block 52 and each abutment is so positioned that it will contact with the member 54 when the same is moved forward. Thus, if one of the cams 14 has engaged with any of the five pairs of arms 15, that particular pair will be freed in readiness to allow the corresponding shaft to move backwards.

By rotating the collar 11, Fig. 1, any particular shaft of the five selectable shafts 16, 18, 20, 21 and 22 may be selected, and is released by moving the clutch-pedal 1.

It is essential that the arrangement of cams 14 on the cam-disc 13 should be such that only one shaft at a time can be selected. Referring now more particularly to Figs. 2 and 4 and assuming that it is desired to engage the reverse gear, the collar 11 is rotated until one of the cams 14 causes the pawl 49 co-operating with the shaft 16 to be brought into readiness for withdrawal as described above. The clutch pedal 1 is pressed and the block 27 and fork 27A are then free to move backwards under the action of the spring 30.

If, now, it is desired to engage the first gear, the collar 11 is again turned until a cam 14 engages between the arms 15 associated with the shaft 22. The clutch-pedal is again actuated and the block 27 on the shaft 16 is drawn back into its neutral position shown in Fig. 2, and its co-operating pawl 49 will lock it in that position. Simultaneously with this locking movement, the pawl 49 will be freed from the selected shaft 22 and the latter will move backwards and, by reason of the lever 23, will move the shaft 17 forwards. The front end of the sleeve 25 will eventually encounter the saddle 38 and will carry the same forward, its striker 42 moving to a position 42a, see Fig. 2, in which the first gear will be engaged.

If it is now desired to engage the second gear, the collar 11 is again rotated in order to release the shaft 18, the release of the latter which is completed by the clutch pedal stroke taking place simultaneously with the return of the striker 42 to its neutral position by means of a pin 60 fixed in the shaft 17. The shaft 18 now moves further backwards, the block 28 contacting with the lateral extension 40 and carrying the striker fork 42 into a position 42B in which the second gear is engaged. Return of the fork 42 to the neutral position is effected by a pin 61 integral with the shaft 18 when the shaft 18 is moved back to neutral by the disc 54.

The engagement of the third and fourth gears by the fork 43 is effected in the same way as in the case of the fork 42, said fork 43 being carried forward to its position 43A (third gear), consequent upon release of shaft 21, by the block 25 on the shaft 19 and returned by a pin 62, and backward to position 43B (fourth gear) by block 29 and returned to neutral position by a pin 63.

Any suitable connection may be made from the collar 11 to a selector control-handle 64 adapted to be mounted in the vicinity of the steering column of the automobile. For convenience, a segmental strip 65 may be provided in which notches 66 are cut corresponding to the different shafts selected and gear engagements desired.

Although with the selecting mechanism described above it is impossible to release a shaft without first returning any shaft which might be out of its neutral position, in order to prevent

any possibility of two gears being engaged at once an additional locking device is arranged on the end-plate 8, see Figs. 1, 2 and 3. A plate 67 is secured to the end-plate and is spaced from the latter by distance-pieces 68. Pivots 69 are arranged between the plate 8 and plate 67, and support four T-pieces 70. As previously mentioned, in Fig. 2 the mechanism is shown in its neutral position, and it will be noted that the shafts 16, 17, 18, 19 and 20 have grooved or tapered parts 71, 72, 73, 74 and 75 respectively, which are adjacent when the shafts are in neutral position. If any one of the shafts is moved axially, the position of its grooved or tapered part is changed and the T-piece immediately adjacent to it will be swung laterally, any such movement being conveyed to all the other T-pieces by reason of their contracting lower ends, see Fig. 2. The result is that all the unmoved shafts are locked in neutral position by the co-operation of the T-pieces with their grooved or tapered parts.

Referring now to the constructional modifications illustrated in Figs. 8, 9, 10, 11 and 12, a casing-like structure 76 supports three shafts 77, 78, and 79, fixedly secured in said casing by means of nuts and washers. A shaft 80 in connection with the clutch-pedal of the automobile passes through the centre of the casing 76, and has secured to it a heavy plate-member 81. The latter is pivotally secured to one end of an adjustable connecting link 82, the other end of which is pivotally connected to a forked lever 83. The latter is mounted on a pivot 84 carried by a supporting member 85 which is fixed by the casing 76. The two upper arms 86 and 87 of the lever 83 pass on either side of the central shaft 78, as shown in Figs. 10 and 11, and are adapted to contact with pins 88 and 89, shown in chain-dotted lines in Fig. 9, carried by saddle members 90 and 91, which are slidably arranged on the shafts 77 and 79.

The shafts 77 and 79 support further slidable saddles 92 and 93 each of which is provided with a depending side-plate 94 adapted to co-act with the member 81. The slidable saddles 90, 91, 92 and 93 are respectively provided with claw-like extensions 95, 96, 97, and 98 the extensions 95 and 97 together controlling a fork 99, Fig. 8, by co-operation with sliding collars 100 and 101 connected by a flat strip 102 on which the fork is carried. The extensions 96 and 98 control collars 103 and 104 slidable on the shaft 79 and connected by a flat strip 105, Fig. 12, which carries a fork 106, see Fig. 8.

The centre shaft 78 carries a single member 107 Figs. 8 and 12, to which a fork 108A is connected, the member 107 extending almost the length of the shaft and being slidably supported upon the latter by means of collars 108 and 109. In each case the connecting strip and collar may be joined by being formed integrally as shown, or otherwise, whilst the various forks may be either formed integrally with the connecting strips or bolted as shown in Fig. 8.

The shaft 78 is shouldered at 110 and the shafts 77 and 79 are flattened at 111 and 112, as shown in Fig. 9 to allow a member 113 to be securely fixed upon the shaft 78. A spring 114 is mounted between the member 113 and the collar 108. Springs 115, 116, 117 and 118 are also provided so that each saddle of the pairs of saddles 90 and 92 and 91 and 98 is drawn towards the saddle opposite it and on the same shaft. The member 107 is provided with an abutment 119 which is adapted to co-operate with the plate-member 81.

When in its neutral position, as shown in Figs. 8, 9 and 10, the member 107 is constantly tending to move in the direction indicated by the arrow H in Fig. 8 by reason of the compression spring 114 but is prevented from doing so, however, by a pawl 120 which engages a ridge 121 formed on the under side of the collar 109. The saddles 92 and 93 are also provided with ridges 122 and 123 respectively (see Fig. 11) which, by co-operation with pawls 124 and 125, resist the tendency of springs 116 and 117 to draw them backwards (i. e. in a direction away from the clutch-pedal). There are therefore three pawls 120, 124 and 125 controlling the centre member 107 and the two saddles 92 and 93 at the particular end of the 15 casing under consideration. For the release of the three pawls a sector 126 is fixedly mounted upon a shaft 127 and has arranged upon its periphery cams 128, Fig. 11. The arrangement for the selection of the required striker forks by 20 means of these cams is exactly the same as in the construction described above and comprises a pair of feeler arms 129 for each of the pawls.

The saddles 90 and 91 are also provided with locking pawls 130 and 131 engaging against ridges 132 and 133 formed upon the saddles as shown in Fig. 10. The shaft 127 is provided with a further cam sector-plate 134, the cams of which co-operate with pairs of feeler arms 129 controlling the pawls 130 and 131. In this case also, the 30 selection and release of the saddles 90 and 91 is accomplished as in the construction described above with reference to Figs. 1 to 7.

The striker fork 108A is intended to engage the reverse gear, the fork 106 the third and fourth 35 gears and the fork 99 the first and second gears. The cams on the plates 134 and 126 are relatively arranged so that only one member at a time can be selected and also so that there is a neutral position. In Fig. 11, the positions of the parts 40 correspond to the selecting positions of the cam-plates.

When it is desired to engage the reverse gear for example, the shaft 127 is rotated until a cam 128 on the plate 126 engages between the feelers 45 129 and thus causes the pawl 120 to be placed under spring pressure tending to withdraw it from contact with its abutment 121. The contact pressure however, is so considerable that the pawl cannot be disengaged until the pressure of the 50 spring 114 is momentarily counteracted by the pressure of the member 81 against the abutment 119, which takes place upon the depression of the clutch-pedal (not shown). The pawl 120 then rapidly swings out of its locking position and 55 the member 107 and striker 108A move backwards to the gear-engaging position under the action of the spring 114. If it is now desired to engage the first gear, the shaft 127 is again rotated until the pawl 125 is brought into a spring-pressed and 60 releasable position. As soon as the clutch-pedal is fully depressed, the member 107 is returned to its original position by the contact of the plate 81 with the abutment 119, the final movement of the plate causing said member 107 to be positively 65 relocked in neutral position and the saddle 92 to be unlocked. The latter moves backwards under the action of its spring 116, encounters the collar 101 and thus carries the fork 99 along with it, the collar 101, which is connected to the collar 104, 70 being free to move backwards within the claw-like extension 95 for a sufficient distance to allow the backward movement to be fully accomplished. The free movement of the collar 100 in the extension 95 results in the saddle 90 when moved 75

having a lost-motion to overcome. The saddle 92 is similarly arranged so that there is also lost-motion to overcome equal to a distance greater than the distance of travel of the fork 99 forwards.

If it is now desired to engage the second gear, the shaft 127 is further rotated until one of the cams on the plate 134 co-operates to make the saddle 90 releasable, whereupon movement of the member 81 by the clutch-pedal will return and relock the saddle 92 so that the fork 99 is restored to its neutral position. At the same time, the saddle 90 is unlocked by the contact of the lever 86 with the pin 88 and slides forward under its spring 115. After having overcome its lost motion the saddle engages the collar 100 and carries the fork 99 forward to its gear-engaging position.

The selection and engagement of the third and fourth speeds is carried out by the release and subsequent movement of the saddles 91 and 98 respectively, in precisely the same way as in the case of the saddles 92 and 90.

To ensure that two gears shall not be engaged at the same time, the fixed member 113 carries on pivots 136 two L-pieces 137 and 138 which are arranged on opposite sides of the member 107 with their horizontal limbs meeting above the latter as shown in Fig. 10. The strips 102 and 105 associated with the forks 106 and 99 and the member 107 are formed with recesses 137^a, 137^b, and 137^c, as shown in Fig. 12 so that when one of the forks or said member is moved axially, the vertical limb of the L-piece which normally engages in one of the said recesses is moved aside, whilst the horizontal parts of said pieces contact to force the vertical limbs into intimate contact with the other unmoved fork and/or member.

Figs. 13 to 17 illustrate a further form of the invention in which the clutch-pedal of the automobile is so connected as to impart movement to the mechanism in two directions, as will appear hereinafter. In this construction, the casing is formed integral with the main gear-box casting and is closed by a cover 140. Three splined shafts 141, 142 and 143 are secured in the casing, the shaft 141 carrying a slidable saddle 144, the shaft 142 two similar saddles 145 and 146 and the shaft 143 also two similar saddles 147 and 148.

The saddles are actuated by means of heavy plate members 149 and 150, see Fig. 16 which are carried upon slidable shafts 151 and 152, which, through flexible connections 153 and 154 are pivotally secured at 155 and 156 to the opposite ends of a centrally-pivoted lever 157. The latter is secured to the clutch-pedal 158, so that when the latter is pushed down to force the clutch out of engagement, the shaft 151 moves forwards and the shaft 152 moves backwards.

Two lugs 159 and 160, Figs. 13 and 16, are formed on the inside of the cover 140 and carry pivots 161 and 162 upon which two pairs of arms 165, 166 and 163, 164 are supported. Each of the arms is free upon its pivot and a tension spring 167 is anchored between each pair of arms 166 and 164 and 165 and 163. The ends of the arms abut against pins 168, 169, 170 and 171 which are respectively fixed in the saddles 145, 147, 146 and 148, so that the saddles of each pair of saddles 145, 146 and 147 and 148 tend to move towards each other. Such movement is rendered impossible, however, by a locking arrangement such as used in the above described constructions and which comprises pawls 172 adapted

to engage ridges 173, see Figs. 13 and 14, formed on the saddles. The pre-selection and disengagement of the pawls 172 is carried out as in the above-described constructions by the co-operation with feelers 300 of cams 174 on sector cam-plates 175. In this construction, however, the release of contact-pressure between a pawl and a ridge so as to allow a saddle to be freed, is effected by the members 149 and 150. The latter are provided respectively with raised working faces 176 and 177, the face 177 being adapted to contact with abutments 178 and 179 on the saddles 146 and 148, and the face 176 with abutments 180 and 181 on the saddles 144 and 145, and with a lateral abutment 182 on the saddle 147. In this way, when the clutch-pedal lever 158 is pressed down each of the saddles momentarily has the spring-pressure upon it released, so that any particular saddle which has been selected will have its restraining pawl 172 withdrawn from its ridge 173 and will move inwards under the action of its spring.

The saddle 144 is formed integrally with a selector or striker fork 182A being intended merely to engage the reverse gear, and its spring 183 is arranged between the collar 184 and the fixed member 185. The collar 184 is integrally connected with the saddle 144 by reason of a flat strip 186 as shown in Figs. 14 and 16.

The saddles 145, 147, 146 and 148 are provided respectively with claw-like extensions 186A, 187, 188 and 189, an opposite pair of such extensions jointly controlling one striker fork. Thus, the extensions 189 and 187 operate the striker fork 190 associated with the engagement of the third and fourth gears, whilst the extensions 186A and 188 operate the striker fork 191 controlling the first and second gears. Both the striker forks 190 and 191 are moved as in the previous construction and are provided with strip-like parts 192 and 193, the ends of which are integral with square section collars 194 and 195 and 196 and 197 respectively.

The selection of the saddles is carried out by two sectors cam plates 175, as already described, said plates being carried at opposite ends of a shaft 198 turnable in the cover 140.

When it is desired to engage any particular gear, the shaft 198 is rotated until one of the cams 174 acts to bring the corresponding saddle into the releasable position. Depression of the clutch-pedal lever 158 then causes the members 149 and 150 to contact with the abutments on all the saddles and to return any one which has previously been displaced. The spring-pressure on all the saddles is also momentarily released so that the selected saddle can move backwards or forwards into its gear-engaging position under the action of its spring.

The shaft 198 is conveniently made operable from the steering-wheel of the automobile.

L-pieces 199, see Figs. 13, 14 and 16, are pivotally attached to the member 185 and pass between the strips 186, 193, and 192. As shown in Fig. 14 the strips are so shaped and the shanks of the L-piece so proportioned that movement of one of the strips will cause the contacting heads of the L-shaped pieces to coat and to lock the other two strips in the neutral position.

The arms 163, 164, 165 and 166 are provided with a series of holes 200, whereby the tension of the springs 167 may be adjusted.

Figs. 18 and 19 show an alternative arrangement of the striker-fork control. The fork 201 is here secured at its two collar-like ends 201A

and 201B to a feathered shaft 202 by means of pins 203. Saddles 204 and 205 jointly control the fork 201 and the movement of one or other of the saddles results in the shaft 202 being carried backwards or forwards as the case may be. The shaft 202 is provided with a groove 206 and the other shafts (shown in Fig. 19) parallel to the shaft 202 are also provided with similar grooves 206A and 206B. The vertical shanks of pivoted L-pieces 207 co-operate with the said grooves in order to lock those shafts which are not to be moved when the other shaft is moved, as described above.

Fig. 20 illustrates a further method of controlling a striker fork 208 keyed to a feathered shaft 209. The latter is provided with enlarged parts 210 and 211, such that when a saddle 212 of the pair of saddles 212 and 213 is released it carries the shaft 209 and striker 208 forward, for instance. If the forward movement is not actually limited by the gear engagement, it will be limited by the saddle 213 abutting against the casing of the mechanism. In order to return the striker 208 to its neutral position a spring (not shown) is provided for pulling the saddle 212 backwards, the saddle abutting against the part 210 of the shaft 209, and, as soon as it is able to do so, returning the shaft and striker to their neutral positions.

In the two first described constructions of the selector mechanism, the striker forks were only moved one at a time. Such an arrangement is suitable where the gear-box to which the selector is applied is of the synchro-mesh or epicyclic type, especially as in all cases the gear-engaging movement is not positive but only under spring action. In a modification, however, the construction could be modified by the introduction of such cam-surfaces on sector cam plates so as to allow more than one striker fork to be selected at a time.

By providing two or more sets of cams and pawls, two or more shafts may be selected and moved simultaneously. In this way, it will be possible to use certain types of gear boxes which hitherto it has not been found practicable to use on account of the complicated arrangement and operation of the gear change lever.

I claim:

1. In mechanism for selectively operating one of a number of normally locked slidable members, the combination of a number of slidable members, locking means for a slidable member comprising a movable locking element and a locking surface on the slidable member engageable therewith, movable means that positively restrain said locking element from movement from such surface in one position of such movable means and in another position to free it from such restraint, means tending to move the locking element after such restraint is removed, means acting when such restraint is moved to exert pressure between member surface and locking element to maintain locking engagement thereof, such pressure being superior to the force acting to free the locking engagement during the period when such restraint is removed, and operator-operated means to release such pressure and leave the slidable member free to slide.

2. Mechanism as in claim 1 in which the coacting surfaces of shoulder and locking element have slidable friction contact.

3. In mechanism for selectively operating one of a number of normally locked slidable members, the combination of a number of slidable

members, means comprising a movable locking element and a surface on the slidable member engageable therewith, means holding said locking element and surface positively in engagement, means freeing such positive engagement while retaining element and surface in locking relation, and subsequently acting means effecting the separation of locking element and surface.

4. Mechanism as in claim 3 having operatively connected with the locking element two spring-actuated movable members in opposed relation that respectively act to positively hold said locking element in locking engagement and free it for subsequent releasing movement, and operator-operated means controlling movement of said members.

5. In mechanism for selectively operating one of a number of normally locked slidable members, the combination of a number of slidable members, means comprising a movable locking element and a surface on the slidable member engageable therewith, means holding said locking element and surface positively in engagement, means freeing such positive engagement while retaining element and surface in locking relation, subsequently acting means effecting the separation of locking element and surface, and means tending normally to move the slidable member in the direction to hold said locking element and said surface in locking engagement.

6. Mechanism as in claim 3 having operatively connected with the locking element two spring-actuated movable members in opposed relation that respectively act to positively hold said locking element in locking engagement and free it for subsequent releasing movement, operator-operated means controlling movement of said members, and spring means acting on the slidable member normally to hold surface and locking element in locking engagement, said spring means exerting a pressure sufficient to overcome the force of the spring acting on said movable member.

7. In mechanism for selectively operating one of a number of normally locked slidable members, the combination of a number of slidable members, means comprising a movable locking element and a surface on the slidable member engageable therewith, a pair of opposing pivoted arms operatively connected with said locking element and movable independently of one another, spring means acting on said arms tending to move them towards one another, and an operator-operated device adapted to impart movement to said arms.

8. In mechanism for selectively operating one of a number of normally locked slidable members to effect the engagement and disengagement of gear wheels, the combination of a pair of such members movable in opposite directions to cause the engagement and disengagement of two different sets of gear wheels, an operating connection between said members, and an additional slidable member adapted to control engagement and disengagement of another set of gear wheels.

9. In mechanism for selectively operating one of a number of normally locked slidable members to control the engagement and disengagement of the gear wheels of a four speed and reverse gear box, the combination of a pair of interconnected slidable members adapted to control the engagement of the first and second gears, a pair of interconnected slidable members adapted to control the engagement of the third and fourth gears,

and an independent slidable member adapted to control the engagement of the reverse gear.

10. In mechanism for selectively operating one of a number of normally locked slidable members to control the engagement and disengagement of the gear wheels of a four speed and reverse gear box, the combination of a pair of interconnected slidable members adapted to control the engagement of the first and second gears, a pair of interconnected slidable members adapted to control the engagement of the third and fourth gears, an independent slidable member adapted to control the engagement of the reverse gear, spring means for moving all the slidable members to operative position, and operator-actuated means to return said slidable members to their original position.

11. In mechanism for selectively operating one of a number of normally locked slidable members to control the engagement and disengagement of the gear wheels of a four speed and reverse gear box, the combination of a fixed shaft, a pair of interconnected slides mounted on said shaft adapted to control the engagement and disengagement of the first and second gears, a second fixed shaft, a pair of interconnected slides mounted on said second fixed shaft adapted to control the engagement and disengagement of the third and fourth gears, a third fixed shaft and a slide mounted thereon adapted to control the operation of the reverse gear.

12. Mechanism as claimed in claim 1, in which one or more of the members to be moved are adapted to occupy two operative and neutral positions, one operative position on one side of a neutral position and the other on the other side thereof, and means to cause the same to take such positions.

13. Mechanism of the character described, having slidable members, and locking means with a movable lock element, selecting devices for the locking means loosely connected with the respective lock elements and means associated with the selecting devices that tend to withdraw their associated lock means from locking position.

14. Mechanism as claimed in claim 13, having the locking and selecting devices each comprise a pivoted lever or levers, spring means adapted to act on said levers, the selecting lever or levers being movable independently of the locking device.

15. Mechanism of the character described for the engagement and disengagement of gear wheels, said mechanism comprising at least one pair of interconnected oppositely movable slidable members adapted by movement in opposite directions to cause the engagement and disengagement of two different sets of gear wheels, and comprising a further slidable member adapted to control the engagement and disengagement of another set of gear wheels.

CHARLES HUMPHREY HUMPHREYS.
